US00D958868S

(12) **United States Design Patent** (10) Patent No.: **US D958,868 S**
(45) Date of Patent: **** Jul. 26, 2022**

(54) **CAMCORDER**

(71) Applicant: **Shenzhen Zhiyong Industry Co., Ltd.**,
Shenzhen (CN)

(72) Inventor: **Guanzheng Zhang**, Shenzhen (CN)

(73) Assignee: **SHENZHEN ZHIYONG INDUSTRY
CO., LTD.**, Shenzhen (CN)

(**) Term: **15 Years**

(21) Appl. No.: **29/701,364**

(22) Filed: **Aug. 11, 2019**

(30) **Foreign Application Priority Data**

Apr. 16, 2019 (CN) 201930172331.7

(51) LOC (13) Cl. **16-01**
